COMBINED LAMP BASE AND BOOK RACK

George D. Brown, 7001 Bancroft St., Toledo, Ohio

Filed Mar. 23, 1964, Ser. No. 79,131

Term of patent 14 years

(Cl. D48—20)

FIGURE 1 is a top perspective view of the combined lamp base and book rack showing my new design; and FIGURE 2 is a side elevation thereof.

The dominant features of my new design are shown in full lines. The undisclosed side and end of the base are substantially the same in appearance as the side and end shown.

I claim:

The ornamental design for a combined lamp base and book rack, substantially as shown and described.
